C. E. WOODS

PHONOGRAPH

Filed May 1, 1920

Clinton E. Woods Inventor:
By his Attorney

Philippine Islands

UNITED STATES PATENT OFFICE.

CLINTON E. WOODS, OF WATERBURY, CONNECTICUT, ASSIGNOR TO SCOVILL MANUFACTURING COMPANY, OF WATERBURY, CONNECTICUT, A CORPORATION OF CONNECTICUT.

PHONOGRAPH.

Application filed May 1, 1920. Serial No. 378,034.

To all whom it may concern:

Be it known that I, CLINTON E. Woods, a citizen of the United States, residing at Waterbury, county of New Haven, and State of Connecticut, have invented certain new and useful Improvements in Phonographs, fully described and represented in the following specification and the accompanying drawings, forming a part of the same.

10 This invention relates to phonographs.

It is an object of the invention to provide simple and effective means for timing the speed governor and for adjusting the timing means.

15 It is a further object of the invention to provide a phonograph that is capable of being conveniently and quickly assembled.

With these general objects in view, the invention consists in the combinations, details 20 of construction and arrangement of parts which will first be described in connection with the accompanying drawings and then more particularly pointed out.

In the drawing,

25 Figure 1 is a plan view with parts broken away of a phonograph constructed in accordance with the invention;

Figure 2 is a view in vertical section;

Figure 3 is a fragmentary sectional view

30 through the controllers;

Figure 4 is a view, in longitudinal section, taken just above the cabinet shelf; and

Figure 5 is a cross-sectional view taken on the line 5—5 of Fig. 3.

35 Referring to the drawing, above the cabinet shelf 11 rotates a turntable 12, mounted on a motor driven spindle 13. In the particular embodiment illustrated, this spindle is journaled in a boss 14 and a bearing bracket 15. This base plate, as appears in

40 Fig. 2, has a diameter greater than the opening in the cabinet shelf, so that the base plate, carrying the motor mechanism, may be suspended from the top of the cabinet shelf. The spindle is shown as having

45 worm teeth 17 and is driven through any suitable connecting train from a drive gear 18. This latter is rotated in known manner by a motor spring indicated conventionally by the spring housing 19.

50 There is provided a centrifugal speed governor. Although capable of various constructions, in that here shown, rotating with the spindle 13 is a gear 21 meshing with a toothed governor shaft 22. Governor

weights 23 are carried on flexible bows 24 mounted on upper and lower collars 25, 26. The upper collar 25 is fast on shaft 22 and the lower collar 26 is slidable on the shaft. The lower collar carries a brake disk 60 27 adapted to cooperate with a frictional brake shoe 28. As the speed of the spindle increases, the weights, moving outwardly, bend the bows 24 and lift the brake disk towards the brake shoe, contact of these 65 braking members serving to limit the speed.

The invention in its entirety includes timing mechanism for setting the governor to give different speeds. This may be accomplished, for example, by shifting the position of the brake shoe 28. Although capable of various constructions, in that here illustrated, the brake shoe is mounted on one arm of a bell-crank lever 29 pivoted on a part of the bracket 16. The other end of 70 the bell crank 29 is connected by a link 30 with a pin 31 extending through an opening 32 in the base plate. The pin 31 is mounted on one end of a bell crank lever 33 located above the base plate and pivoted 75 on a pin 34 carried by the baseplate. The other arm of the bell crank 33 is connected by a connecting rod 35 with a timing controller.

80 The timing controller, in the present exemplification, includes an operating knob 36 pinned to a stud 37 mounted in a bracket 38 hereinafter referred to. The connecting rod 35 is eccentrically pinned to the stud 37 by a screw 39. The bracket 38 may have 85 an indicating dial as shown in Fig. 1.

When it is desired to speed up the turntable, the controller knob is turned (clockwise in Fig. 1) to pull the connecting rod 35 forward. Through the connections described, this swings bell-crank 29 to raise the brake shoe 28 further away from the brake disk 27. When the controller knob is turned in the opposite direction to reduce speed, the parts are moved reversely by the force of a spring 40 connected to bell crank 29 and the brake shoe is brought nearer the brake disk. 100

105 A spring 41 located between the bracket 38 and a washer 42 carried by stud 37 serves to hold the parts in the position given.

In the order that the governor may give the true speed indicated, the invention includes means for adjusting the timing mechanism for a given timing position. This may be accomplished, for example, 110

2 by adjusting the effective length of the connecting rod 35. Although capable of various constructions, in the embodiment here shown, the end of the connecting rod 35 is 65
slidable in the arm of the bell crank 33. To adjustably hold the parts in given relation, threaded into the end of the connecting rod, beyond the bell crank arm, are an adjusting nut 43 and a lock nut 44. By shifting these 70
10 nuts the effective length of the connecting rod may be varied to adjust the position of the brake shoe for a given position of the controller knob. This construction provides a convenient means of giving the parts an 75
15 initial adjustment or of readjusting them in case, from wear or the like, the true speed varies from the indicated speed.

Structures embodying the invention in its 80
entirety include a controller unit comprising 20
a timing controller, a brake controller and a bracket adapted to be secured to the cabinet shelf. An exemplification of a timing controller has already been described. The 85
25
brake controller also may vary in construction. In the particular embodiment illustrated, rotatably and slidably mounted in a housing 47 is a shaft 48 bearing at its end a frictional brake shoe 49 adapted to engage the edge of the turntable. Part of the 90
30
shaft 48 is flattened on opposite sides, as at 50, and the flattened portion is embraced by a controller handle 51, so that movement of the handle tends to rotate the shaft. Means is provided for causing the shaft, upon operation of the controller handle, to have a longitudinal displacement. As shown, as an 95
35
example, the shaft is formed with a half or partial helical groove 52 in which rides a pin 53 adjustably mounted in the housing 47. When the shaft is rotated by the controller handle, therefore, it will also be displaced longitudinally, thus moving the brake 100
40
sleeve into or out of braking engagement to stop or start the turntable. A spring 54 holds the parts in given position.

Although the bracket, hereinbefore referred to generally as 38, may have various constructions, as here shown, it is a casting having a top portion 55 and a downturned 105
50
flange or leg portion 56 for supporting it on the shelf. The top at one side is higher than the other to provide a housing for the parts of the timing controller already described. The housing 47 of the brake controller element is secured to the bracket by a screw 57 or the like.

With the construction described, the unit comprising the brake controller, the timing controller and the supporting bracket may 110
60
be assembled apart from the cabinet. Likewise the motor mechanism may be assembled as a unit. Then it is only necessary to drop the motor unit into the shelf opening, so it is suspended by the base plate from the top

of the shelf to secure it in place, as by 65
screws 45. The controller unit is then secured to the shelf, as by screws 46. After connecting rod 35 to bell crank 33, the turntable may be placed on the spindle. The construction described, therefore, by providing only two independently assembled 70
75
units simplifies greatly the assembly of the various mechanisms with the cabinet.

What is claimed is:

1. In a phonograph, in combination with 75
a turntable spindle and driving means therefor, a centrifugal speed governor for controlling the spindle speed including cooperating 80
braking elements one of which is normally stationary and the other movable with the spindle, a bell crank lever on which said stationary brake element is mounted, a second bell crank lever connected to the first lever, a rotatable timing controller, a connecting rod eccentrically mounted on said controller and connected with said second bell crank lever, and a connection between the two levers.

2. In a phonograph, in combination with 85
a turntable spindle and driving means therefor, a centrifugal speed governor for controlling the spindle speed including cooperating 90
braking elements one of which is normally stationary and the other movable with the spindle, a bell crank lever on which said stationary brake element is mounted, a second bell crank lever connected to the first lever, a rotatable timing controller, a connecting rod eccentrically mounted on said 95
controller and adjustably connected with said second bell crank lever.

3. In a phonograph, in combination with 100
a cabinet shelf, a turntable and a driven 105
spindle therefor, a controller unit secured to the cabinet shelf and comprising a timing controller, a brake controller and a supporting bracket for said controllers.

4. In a phonograph, in combination with 110
a cabinet shelf having an opening therein, a motor unit comprising a turntable spindle, driving means therefor and a supporting 115
base plate adapted to be suspended from the top of the cabinet shelf, and a controller unit secured to the cabinet shelf and including a timing controller, a brake controller and a supporting bracket for said controllers.

5. In a phonograph, in combination with a 120
base plate adapted to be suspended from a cabinet shelf, a turntable spindle and a motor unit suspended from said base plate, and a controller unit adapted to be secured on the base plate and including a timing controller, a brake controller and a brake for engaging the periphery of a turntable.

In testimony whereof, I have hereunto set 125
my hand.

CLINTON E. WOODS.
